CLAIM

The ornamental design for a computer desk, as shown and described.

DESCRIPTION

FIG. 1 is a top, front perspective view of a computer desk, showing our new design;

FIG. 2 is a bottom, rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front perspective view, showing the computer desk in an alternate configuration of use;

FIG. 10 is an enlarged view of detail 10 in FIG. 1; and,

FIG. 11 is an enlarged view of detail 11 in FIG. 1.
